C. A. WULF

VAPORIZER FOR HYDROCARBON ENGINES

Filed Sept. 3, 1920

Patented Dec. 18, 1923.

1,478,092

UNITED STATES PATENT OFFICE.

CHARLES A. WULF, OF INDIANAPOLIS, INDIANA.

VAPORIZER FOR HYDROCARBON ENGINES.

Application filed September 3, 1920. Serial No. 407,900.

To all whom it may concern:

Be it known that I, CHARLES A. WULF, a citizen of the United States, residing at Indianapolis, in the county of Marion and 5 State of Indiana, have invented new and useful Improvements in Vaporizers for Hydrocarbon Engines, of which the following is a specification.

The object of this invention is to take 10 the hot vapors from the radiator overflow-pipe without interfering with the other functions of the pipe, and supply it to the intake manifold of the engine in quantities regulated by a valve opened and closed by 15 a thermostat in turn influenced by the heat generated by the hydrocarbon explosions, and without danger of introducing water into the mixture to deaden it.

The object is to provide a thermostatic 20 control that will hold the valve of the steam supply closed at the starting of the engine and until heat enough has been developed to insure beneficial results by the introduction of the requisite quantity of steam 25 as the engine runs fast or slow and its requirements vary.

Another object is to provide means for regulating a thermostatic spring controlling the valve, to prevent chattering noises at 30 some speeds of the engine, caused by the rapid seating and unseating of the valve.

The object further is to provide a simple device with but two moving parts so constructed that a novice can install them, and 35 can take the valve apart and reassemble it without danger of making a mistake.

I accomplish the above, and other objects which will hereinafter appear, by the mechanism illustrated in the accompanying 40 drawing, in which—

Figure 1, is an illustrative view showing the application of my invention. Fig. 2, is a top plan view of the valve and appurtenant parts. Fig. 3 is a view of same 45 with the housing removed and looking in the direction of the arrows 3—3 of Fig. 2. Fig. 4 is a sectional view through the thermostat and valve on the line 4—4, of Fig. 1, and Fig. 5, is a detached view of the 50 coupling to the radiator-overflow pipe.

Like characters of reference indicate like parts in the several views of the drawing.

Referring to the drawings, the numeral 6 refers to an engine provided with the 55 usual adjuncts, as an inlet manifold 7, communicating with a carburetor 8, and the

combustion chamber of the engine, and an exhaust manifold 9, through which the exhaust products of combustion pass. The interior mechanism of the engine is not 60 shown as it may be of any well known type of construction.

The radiator 10, of usual construction, has the usual overflow pipe 11, the length of which I extend by attaching a short pipe 65 12, to its lower end by means of a rubber sleeve 13, or other suitable means. This pipe 12 has a lateral branch 14, midway of its length or sufficiently above its lower end to avoid drawing water into the branch 70 by suction, and so as not to interfere with the normal action of the pipe 12 as an overflow drain to the radiator.

Secured to a hot part of the mechanism, here shown as bolted to the exhaust manifold 9, is a bracket 15, having a barrel 16, with a bore in which the body-portion 17, of a valve-stem makes a close sliding fit. The inner end of the bore of the barrel is reduced and continued through a nipple 80 18. The stem is reduced and terminates with a conical valve as shown in Fig. 4 which is seated at the junction of the large and small bores of the barrel, as shown in Fig. 4. The reduced inner diameter of the 85 valve stem provides a chamber into which a lateral hole of approximately the same diameter as the reduced bore of the barrel discharges. This lateral hole is continued through a nipple extension 19. Both nipples 18 and 19, are screw-threaded to receive screw-caps 20, by which pipe lines 21 and 22, respectively, are connected. The other end of the pipe line 22, is connected with the lateral branch 14 of the pipe 12 95 extension of overflow pipe 11. The other end of the pipe line 21, is connected with a screw-cap 23 on a nipple screwed into a hole through the inlet manifold 7, as shown in Fig. 1.

Formed on the bracket 15, at the end of barrel 16, is a plate 24, with outwardly disposed end flanges 25, 25, the ends of which are preferably tapered on the outside to facilitate the insertion over them of a box-cap 26. Secured to the plate 24, by screw 27, is a leaf spring 28, formed of two laminations of different metals of widely different expansibility when heated, here shown as iron and brass, with the brass member *b*, 110 toward plate 24, and iron *a* more remote. This spring is bifurcated at its free end

and enters an annular groove 29, in the suitably extended end of valve stem member 17. The groove is at an appreciable distance out from the adjacent surface of plate 24, when the valve is seated to enable the spring when cold to positively seat the valve, and the space thus provided allows for the proper assembly of a bearing-plate 30 at the other end of the spring between 5 the spring and plate. The bearing-plate 30 preferably has a flange 31 on which the end of the spring 28 is fulcrumed, thereby enabling the spring to be tensioned by means of the screw 27. Because it is necessary that spring 28 be assembled with the brass side *b*, toward plate 24, I form a lug 32 on plate 24, requiring the spring 28 to be correspondingly clipped to fit it, which makes assembly impossible except in the 10 right way.

The operation of my invention is as follows: When the engine is started cold and it is not desirable to have the above communication into manifold 7 open, the valve 15 is seated by spring 28, and communication is closed. But when the engine gets hot the 20

valve is opened by the thermostatic action of the spring 28, and any tendency of the valve to chatter is stopped by moving the screw 27. By connecting with overflow pipe 11 through the lateral branch 14, above the end of the pipe, only steam will pass over by the suction of the engine and the water will drain out at the end of the pipe 11 as usual. 25

Having thus fully described my invention what I claim as new and wish to secure by Letters Patent of the United States, is—

In a device of the class described, the combination with a radiator overflow pipe in two parts, a flexible connection between the two parts, the part most remote from the radiator having a lateral branch, an engine intake manifold, a pipe line connecting the lateral branch of the overflow pipe with 40 the manifold, a valve in said line, a thermostat operated by heat from said radiator to open the valve and means in the thermostat to prevent the chattering of the valve. 45

Signed at Indianapolis, Indiana, this the 26 day of August 1920. 50

CHARLES A. WULF.
